United States Patent Office

Des. 232,334

Patented Aug. 13, 1974

232,334

INDEX CARD HOLDER

Hildaur L. Neilsen, Metuchen, N.J., assignor to Zephyr
American Corporation, Long Island City, N.Y.

Filed Jan. 15, 1973, Ser. No. 323,755

Term of patent 14 years

Int. Cl. D6—04

U.S. Cl. D6—140

FIG. 1

FIG. 2

FIG. 3

FIG. 1 is a front elevational view of the index card holder, the rear thereof being identical in appearance;

FIG. 2 is a side elevational view thereof, the opposite side being identical in appearance; and

FIG. 3 is a top plan view thereof.

I claim:

The ornamental design for an index card holder, as shown and described.
